MUFFLER FOR INTERNAL COMBUSTION ENGINES

Douglas Gordon, Erin, Wis., assignor to Briggs & Stratton Corporation, Milwaukee, Wis., a corporation of Delaware

Filed Nov. 7, 1962, Ser. No. 72,419

Term of patent 14 years

(Cl. D14—6)

Fig. 1.

Fig. 2.

Fig. 3.

Fig. 4.

Fig. 5.

FIGURE 1 is a top perspective view of the muffler for internal combustion engines embodying my new design;

FIGURE 2 is a bottom perspective view thereof;

FIGURE 3 is top plan view thereof;

FIGURE 4 is a side elevational view thereof; and

FIGURE 5 is an end view of the muffler for internal combustion engines, viewed from the left in FIGURE 4.

The dominant features of my design reside in those portions thereof shown in solid lines.

I claim:

The ornamental design for a muffler for internal combustion engines, as shown and described.
